CLAIM

The ornamental design for a display screen with graphical user interface, as shown and described.

DESCRIPTION

FIG. 1 is a front view of a display screen with graphical user interface showing the new design; and,

FIG. 2 is an enlarged view of the claimed region of FIG. 1, shown separately for ease of illustration.

The broken line showings of the display screen and of selected regions of the graphical user interface are for environmental purposes only and form no part of the claimed design.
